UNITED STATES PATENT OFFICE.

ANGUS F. HANNEY AND ALEXANDER GAMMELL, OF CHICAGO, ILLINOIS, ASSIGNORS TO
EUREKA ROUGH DRY PIN SYSTEM CO., OF CHICAGO, ILLINOIS.

TAG-RELEASING DEVICE.

Application filed February 1, 1923. Serial No. 616,449.

To all whom it may concern:

Be it known that we, ANGUS F. HANNEY and ALEXANDER GAMMELL, citizens of the United States, and residents of the city of Chicago, county of Cook, and State of Illinois, respectively, have invented certain new and useful Improvements in a Tag-Releasing Device, of which the following is a specification.

10 Our invention relates to a tag releasing device especially designed to be used in connection with a device for assorting rough dry pinned work and has for its principal object the provision of an improved construction of this character which will be highly efficient in use.

Among other objects of the invention is the provision for automatically releasing the laundry supporting tags to facilitate removing the clothes carried by the pins, the provision being of such construction that the clothes are simultaneously released from the supporting tags.

Another object of the invention is the provision for holding the tag supporting rod in position to facilitate releasing the clothes from the tags.

Other objects will appear hereinafter.

The invention consists in the combinations and arrangements of parts hereinafter described and claimed.

The invention will be best understood by reference to the accompanying drawings forming a part of this specification, and in which,

Fig. 1, is a fragmentary side elevational view of the invention;

Fig. 2, is a fragmentary vertical sectional view of the same;

40 Fig. 3, is a fragmentary end elevational view of the same taken substantially on line 3—3 of Fig. 2;

Fig. 4, is a fragmentary plan view of an assorting reel showing the tag supporting rod holders, embodied in the invention, associated therewith;

Fig. 5, is a fragmentary perspective view of one of the contact supporting rods embodied in the invention;

50 Fig. 6, is a fragmentary side elevational view of the rod illustrated in Fig. 5;

Fig. 7, is a fragmentary perspective view of the holder engaging end of the rod illustrated in Fig. 6;

55 Fig. 8, is a fragmentary top plan view of

the holder, embodied in the invention, partly in section;

Fig. 9, is a sectional view of the holder taken substantially on line 9—9 of Fig. 8;

Fig. 10, is a sectional view taken substantially on line 10—10 of Fig. 8 showing the holder with the tag release rod, embodied in the invention associated therewith;

Fig. 11, is a fragmentary sectional view taken substantially on line 11—11 of Fig. 4; 65

Fig. 12, is a side view of the lock, embodied in the invention, which is associated with the holder for locking the tag supporting rod therein;

Fig. 13, is a fragmentary side elevational view of the release rod operating mechanism embodied in the invention;

Fig. 14, is a sectional view of the same taken substantially on line 14—14 of Fig. 13;

Fig. 15, is a side elevational view of a laundry tag used in connection with the combination of the invention;

Fig. 16, is a side elevational view of the motor control lever, embodied in the invention;

80

Fig. 17, is a perspective view of an adjustable plate embodied in the invention; and

Fig. 18, is a detail view of one of the holders embodied in the invention, shown partly in section.

In laundries, commonly known as family service laundries, a system is employed for assorting the rough dry clothes in lots. A common method is the employment of a clothes reel which is mounted for circumferential movement. Associated with this clothes reel there are a plurality of laundry tag supporting rods which support the laundry tags, similar to the tag illustrated in Fig. 15. The laundry tags in turn support the clothes. The present method of removing the clothes, after they have been assorted into various lots, is by removing the laundry tags from their respective supports and then singly removing the tags from the clothes. Considerable labor is lost in doing this and it is primarily our object to provide a device which will automatically, simultaneously release the tags to permit the removal of the clothes therefrom.

Referring to Fig. 4, 20 indicates an assorting reel comprising a circular frame 21 and lateral supports 22. Associated with the frame 21 are holders 23 equally spaced 110

apart and adapted to receive the outer end portions 24 of the tag supporting rods 25, the tag supporting rods being channel shaped in cross section as best illustrated in Fig. 5, 5 for the purposes which will be hereinafter set forth.

Each holder comprises a body portion 26, preferably rectangular in cross section, and provided with a reduced portion 27 adapted 10 to pass through an opening 28 formed in the frame 21 and be held in the position illustrated in Fig. 4, by a nut 29. The holder 23 has a longitudinal passage 30 formed therethrough into which the end 15 portion 24 of the rod is adapted to be inserted a predetermined distance, the distance being determined by a stop pin 31 against which the extremity of the end portion 24 of the rod is adapted to abut. 20 Formed through the holder 23 is a second passage 32 of a smaller width than the passage 30 and in communication with said passage as best illustrated in Fig. 9, for the purposes which will be more fully herein- 25 after set forth.

Means is provided for releasably locking the rod 25 within the holder, this means comprises a transverse pin 33 having an external enlarged portion 34 carrying an operating handle 35, movement of the handle being limited by stop pins 36 and 37 as best 30 illustrated in Fig. 8. As shown in Fig. 12 a portion of the pin, as indicated at 38 is cut away, for the passage of the top portion 35 indicated at 39, Fig. 5, of the end portion 24 of the rod. The end portion 24 of the rod has spaced depressed portions 40 for the reception of the pin 33 when the pin is revolved in the position illustrated in Fig. 40 10, and when the pin is in this position the rod is held against removal from the holder. By turning the pin 33 in the position illustrated in Fig. 9, the turning of the pin being accomplished by the operating handle 35, 45 the cut out portion of the pin is brought into the position illustrated and permits the removal of the rod.

As already stated, the rods 25 are specifically designed for supporting laundry tags 50 similar to that illustrated in Fig. 15. The laundry tag 41 illustrated in this figure is constructed substantially the same as that disclosed in United States Letters Patent No. 1,411,092 issued to Angus F. Hanney, and 55 only such construction will be described as will be necessary to understand its function in combination with the present invention. The tag 41 comprises a pin point 42 carried by a casing 43, a locking lever 44 pivoted at 45 and a spring controlled 60 detent 46 cooperating with the locking lever 44 and having a portion exposed through an opening 47. Through the opening 47 the rod upon which the tag is mounted is adapted 65 to pass and occupy the portion of the

opening above the top edge 46' of the detent 46. The clothes are carried by the tag and are attached thereto by passing the pin 42 therethrough and held in such position with respect to the pin by the locking lever 44 which is held, when in the position illustrated in Fig. 15, against movement by the detent 46, the detent permitting movement of the locking lever 44 from locking position upon being pressed downward by the selective means, the construction of such means being as follows:

The tag unlocking means includes a frame 48 having spaced standards 49 and 50 as best 80 illustrated in Fig. 1.

Associated with the frame 48 and carried by the standards thereof is a channel shaped guide 51 and a reciprocating rod 52 adapted to work in the channel of the guide 51 and provided with a tapered end portion 53. The rod 52 is operatively connected to a sleeve 54 mounted for reciprocating movement on a screw 55 mounted to operate in adjustable bearings 56 carried by the standards, the adjustment of the bearings being accomplished by set screws 57; said bearings being of the approved type now conventionally in use. Mounted to operate in approved bearings 58 is a shaft 59 operatively connected to the motor 60 by means of sprocket gears 61 and sprocket chain 62 of the silent drive type. The screw 55 is operatively connected to the shaft 59 by gears 63 and 64, the arrangement being best 90 illustrated in Fig. 1.

The operation of the construction so far set forth is such that upon operation of the motor 60 the shaft 59 operates the screw 55 and upon rotation of the screw the release rod 52 is caused to reciprocate in the channel guide 51. The release rod when reciprocated in the direction indicated by the arrow in Fig. 1 is adapted to pass through the transverse opening 65 formed through the head of the standard 49. The holders 23 are singly brought into a position such that the passage formed therethrough will register with the opening 65 and when the release rod is reciprocated in the direction indicated, the same will pass through the passage and along the channel of the rod 25 carried by the holder. Upon entering the channel of the rod 25 the release pin engages the detents 46' of the laundry tags supported on the tag supporting rod and automatically causes the detents to release the locking levers permitting the removal of clothes from the pins of the laundry tags. The action of the release rod takes place with such speed that will almost simultaneously permit removal of the clothes from all the pins.

As shown in Fig. 3, the opening 65 is formed in the head of the standard 49 inclined with respect to the sides thereof. The reason for this is that the weight of the 130

clothes has a tendency to tilt the laundry tags and this opening is formed in the manner illustrated to assure true registration of the opening with respect to the passage of 5 each of the holders, the passages of which are adjusted at an angle inclined to the horizontal by turning the holders.

Means is provided for releasably holding, alternately and singly, each of the holders 10 in the position already mentioned. This means comprises a member 66 having a slot 67 formed in its upper extremity and mounted for vertical movement along the front of the standard 59 by a bracket 68 attached to said standard by machine screws 69. The member 66 is held in its initial operative position by means of spring members 70 attached to lugs 71 carried by bracket 68 and to a handle 72 carried at the lower 15 extremity of the member 66. The construction is such that the spring members 70 will return the member 66 from an inoperative to an operative position, the operative position of the member 66 being illustrated 20 in Fig. 3. The vertical slidable movement of the member 66 in an upward direction is limited by a stop pin 72' adapted to abut the lower edge of bracket 68, as shown.

The member 66 is automatically moved 25 from operative position by the holders 23 as each holder is moved into operative position, this being accomplished by beveling the upper corners of the member, as indicated at 73, and providing a lateral projection 30 74 on the face of the standard as indicated in Fig. 3. The outer extremity of the holders when each are singly moved into operative position will engage the adjacent bevelled corner of the member 66 forcing 35 the member downwardly and pass into the slot 67, the member 66 returning to its initial position by action of the springs 70.

Means is provided for varying the width 40 of the opening 67, this means includes a plate 75 having elongated slots 76 formed therein through which machine bolts 77 pass, the plate being mounted for slidable movement on the rear surface of the member 66 and the slots 76 permit adjustment 45 of the plate.

Referring to Figs. 6 and 7 it will be noted 50 that the holder engaging extremity of the rod 25 is provided with an enlarged socket 78. This provision is such that should the channel of the rod be slightly out of alignment with the opening 65 the tapered end 53 of the release rod will pass into the socket and move the holder in the necessary direction to bring proper registration between 55 the passage thereof and the opening 65.

The motor 60 which effects the operation 60 of the release rod is designed to run in clock-wise direction and anti-clock-wise direction and means is provided for con-

trolling such operation of the motor as well as to automatically stop the operation of the motor when the release rod has travelled its full distance. This means comprises a two-way switch 79 having contact members 70 60 80 and 81 connected in circuit with the terminal posts 82 of the motor by conductors 83. The switch also comprises a common contact point 84 carried by a pivotally mounted link 85, said contact member being connected to a suitable source of electrical supply as indicated at 86, the motor 60 being also connected by a conductor 87 to said source of supply. Pivotally connected to one end of link 85 and working through a bracket 88 is a link 89 having a vertical bent end 90. To the other end of the link 85 is connected a link 91 having its free end connected to a pivotally mounted link 92, the link 92 being provided with an operating handle 93. A link 94 is connected to the link 92 and works through a bracket 95 and is provided with an arm 96 similar to the arm 90 and is in alignment therewith.

Carried by the sleeve 54 is a lateral pin 97 which engages the arms 90 and 96 upon completion of its travel along the screw 55. As the sleeve 97 completes its travel in the direction indicated by the arrow, the pin engages the arm 96 causing the link 93 to pivot, which through the medium of the links 85 and 91 brings the contact point 84 from engagement with the contact member 81, breaking the circuit and stopping the 100 operation of the motor. To reverse the operation of the motor, the operator, by manipulating the handle 93 through the medium of the links 85 and 91, brings the contact point into contact with the contact element 80 and the motor operates in the reverse direction causing the sleeve 54 to return to its initial position. Upon returning to its initial position the pin engages the arm 90, and the contact element 84 is again 110 thrown into neutral position, and the operation of the motor stopped. By again manipulating the handle 93 the motor can again be caused to operate. I provide means for determining the pivotal movement of 115 the operating handle to reverse the operation of the motor as above detailed, this means comprises a plate 98 having three depressions 99 formed therein for the engagement with a pin 100 having a rounded extremity 101. By this provision the operator can determine the distance it will be necessary to pivot the link 92 to bring the contact elements of the switch into proper engagement.

While the construction and parts above illustrated is the preferred arrangement for operating the motor it is apparent that any two-way switch which can be incorporated in the combination will serve the purpose as 130

well as any way of reversing the motor and automatically stopping the same.

While we have not illustrated an enclosure for the parts carried by the standards 49 5 and 50 it is to be understood that one can be provided, the closure not being material to the present invention.

From the description herein set forth and from the construction disclosed in the drawings it is apparent that we provide a device which will accomplish the objects of the invention with high efficiency and one which will be economical in manufacture. Further reference need not be made to the function 10 of the device because it is apparent that from the disclosure, the operation of the invention is manifest.

While we have illustrated and described the preferred form of construction for 20 carrying our invention into effect, this is capable of variation and modification without departing from the spirit of the invention. We, therefore, do not wish to be limited to the precise details of construction 25 set forth, but desire to avail ourselves of such variations and modifications as come within the scope of the appended claims.

Having described our invention, what we 30 claim as new and desire to secure by Letters Patent, is:

1. In combination with a supporting reel and a plurality of laundry marking members having releasable means for carrying 35 articles, supporting members on the reel adapted to carry the laundry marking members, and a member adapted to be successively moved along the supporting members and engage the releasable carrying means to 40 release the articles carried by the marking members.

2. The combination with a supporting reel and laundry marking members having releasable carrying means each provided with 45 an opening exposing the catch mechanism of the carrying means, supporting members on the reel adapted to be taken through the openings of the marking members, and a member adapted to be successively moved 50 along said supporting members through the openings of the tag for engagement with the catch mechanism to release the carrying means.

3. In combination with a supporting reel 55 and a plurality of laundry marking members having releasable means for carrying articles, supporting members removably carried by the reel and carrying the laundry marking members, a member adapted to be successively moved along the supporting 60 members and engage the releasable carrying means to release the articles carried thereby, and means for moving said last named member.

4. In combination with a supporting member and laundry marking members having releasable carrying means and openings exposing the catch mechanism of the carrying means, a channel-shaped support carried by the supporting member, and taken through 70 the openings, and a member adapted to be successively moved along the support within the channel and through the openings to engage the catch mechanism to release the carrying means. 75

5. In combination with a support and identification members adapted to releasably carry articles, a channel-shaped member carrying the identification tags and carried by the support, and means adapted to be moved along the support within the channel for engagement with the carrying means of the identification tags to release the articles carried thereby. 80

6. In combination with a support and 85 identification members adapted to releasably carry articles, a channel-shaped member carrying the identification tags and carried by the support, means adapted to be moved along the support within the channel for 90 engagement with the carrying means of the identification tags to release the articles carried thereby, and means for moving said last named means. 95

7. In combination with a support and laundry marking members having releasable carrying means and openings exposing the catch mechanism of the carrying means, a channel-shaped support taken through the 100 openings and carried by the first named support, a member adapted to be successively moved along the supports within the channel and through the openings to engage the catch mechanism to release the carrying means, and means for moving said last 105 named means.

8. In combination with a support and identification members adapted to releasably carry articles, a channel-shaped member carrying the identification tags and removably carried by the support, means adapted to be moved along the support within the channel for engagement with the carrying means of the identification tags to release the articles carried thereby, means for moving said last named means, means for operating said moving means, and means for reversing said operating means. 110

9. In combination with a supporting member and tags having registering openings for the passage of said member and having releasable carrying means and provided with passages communicating with said openings; a reciprocatory actuated member insertable through said passages for 115 releasing said carrying means. 120

10. In combination with a laundry tag having means for carrying an article and a

- lock member for preventing removal of the article; a member mounted for reciprocatory movement and for engagement with said member for releasing said member to 5 permit removal of the article.
11. In combination with a plurality of laundry tags arranged in a row and having means for carrying articles, members adapted to prevent removal of the articles, openings through said tags and members for locking said first named members in operative position and having portions exposed to said openings; a member for engagement with the exposed portions of said second 10 named members to release said first named members and the articles carried by the carrying means.
12. In combination with a laundry assorting device including a clothes assorting reel, supports, holders associated with said reel having central passages for the insertion of the end portions of said supports, and laundry tags removably carried by said supports and having means for releasably carrying articles; a member having a slot for the reception of the outer end portions of said holder; and a member adapted to pass through the passages of the holders and engage said carrying means to release said 15 articles.
13. A device for opening laundry assorting tags having means for releasably carrying articles including a guide, and a member mounted for reciprocation along said guide and adapted to engage the carrying means of the tags to release said articles.
14. A device for opening laundry assorting tags having means for releasably carrying articles including a guide, a member mounted for reciprocation along said guide and adapted to engage the carrying means of the tags to release said articles, and means for reciprocating said member.
15. A device for opening laundry assorting tags having openings registering when the tags are arranged in a row and having means for releasably carrying articles and members for controlling said carrying means, including a guide, a member associated with said guide and adapted to pass through the openings of the tag and engage said controlling members for releasing said holding means to permit removal of the articles, and means for moving said member 50 through said openings.
16. A device for opening laundry assorting tags having openings registering when the tags are arranged in a row and having means for releasably carrying articles and members for controlling said carrying means, including a channel shaped guide, a member working in the channel of said guide and adapted to pass through the openings of the tag and engage said controlling 55 members for preventing removal of the article; a member mounted for reciprocatory movement and for engagement with said member for releasing said member to permit removal of the article.
- members for releasing said holding means to 65 permit removal of the articles, and means for moving said member through said openings.
17. A device for the purposes herein set forth including in combination with a support adapted to carrying laundry marking tags having means for releasably carrying articles, a member mounted for rotation, a member mounted to move longitudinally with respect to said first named member, a member carried by said second named member and extending longitudinally in spaced relation with respect to said first named member and adapted to be moved along the support for engagement with the releasable carrying means of the tags for releasing the articles carried thereby; and a guide for said last named member.
18. A device for the purposes herein set forth including in combination with a support adapted to carrying laundry marking tags having means for releasably carrying articles, a member mounted for rotation, a member mounted to move longitudinally with respect to said first named member, a member carried by said second named member and extending longitudinally in spaced relation with respect to said first named member and adapted to be moved along the support for engagement with the releasable carrying means of the tags for releasing the articles carried thereby; a guide for said last named member; and means for rotating said first named member.
19. A device for the purposes herein set forth including in combination with a support adapted to carrying laundry marking tags having means for releasably carrying articles, a member mounted for rotation, a channel shaped guide member in spaced relation with said member and extending parallel therewith, a member working in the channel of said second named member and adapted to be moved along the support for engagement with the releasable carrying means of the tags for releasing the articles carried thereby, and a sleeve on said first named member and operatively connected to said last named member.
20. A device for the purposes herein set forth including in combination with a support adapted to carrying laundry marking tags having means for releasably carrying articles, a member mounted for rotation, a channel shaped guide member in spaced relation with said member and extending parallel therewith, a member working in the channel of said second named member and adapted to be moved along the support for engagement with the releasable carrying means of the tags for releasing the articles carried thereby, a sleeve on said first named member and operatively connected to said last 100 member.
- 105

- 125

- named member, and means for rotating said first named member.
21. A device for the purposes herein set forth including in combination with a support adapted to carrying laundry marking tags having means for releasably carrying articles, a member mounted for rotation, a channel shaped guide member in spaced relation with respect to said member and extending parallel therewith, a member working in the channel of said second named member and adapted to be moved along the support for engagement with the releasable carrying means of the tags for releasing the articles carried thereby, a sleeve on said first named member and operatively connected to said last named member, and means for alternately rotating said first named member in clock-wise and anti-clockwise direction.
- 20 22. A device for the purposes herein set forth including in combination with a support adapted to carrying laundry marking tags having means for releasably carrying articles, a member mounted for rotation, a member mounted to move longitudinally with respect to said first named member, a member carried by said second named member and extending longitudinally in spaced relation with respect to said first named member and adapted to be moved along the support for engagement with the releasable carrying means of the tags for releasing the articles carried thereby; a guide for said last named member; and means for alternately rotating said first named member in clock-wise and anti-clockwise direction.
- 25 23. A device for the purposes herein set forth including in combination with a support adapted to carrying laundry marking tags having means for releasably carrying articles, a screw threaded member, a member in spaced relation with respect to said screw threaded member and extending in parallel relation with respect thereto and adapted to be moved along the support for engagement with the releasable carrying means of the tags for releasing the articles carried thereby, a sleeve on said screw threaded member and operatively connected to said second named member, and means for rotating said first named member to move said second named member longitudinally with respect thereto.
- 30 24. A device for the purposes herein set forth including in combination with a support adapted to carrying laundry marking tags having means for releasably carrying articles, a screw threaded member, a member in spaced relation with respect to said screw threaded member and extending in parallel relation with respect thereto and adapted to be moved along the support for engagement with the releasable carrying means of the tags for releasing the articles carried thereby, a sleeve on said screw threaded member
- 35 and operatively connected to said second named member, means for rotating said first named member in clockwise and anti-clockwise direction to move said second named member longitudinally with respect thereto.
- 40 25. A device for the purposes herein set forth including in combination with a support adapted to carrying laundry marking tags having means for releasably carrying articles, a screw threaded member, a member in spaced relation with respect to said screw threaded member and extending in parallel relation with respect thereto and adapted to be moved along the support for engagement with the releasable carrying means of the tags for releasing the articles carried thereby, a sleeve on said screw threaded member and operatively connected to said second named member, means for rotating said first named member in clockwise and anti-clockwise direction to move said second named member longitudinally with respect thereto, and means carried by said sleeve for controlling said last named means.
- 45 26. A device for the purposes herein set forth including in combination with a support adapted to carrying laundry marking tags having means for releasably carrying articles, a member mounted for rotation, a member mounted to move longitudinally with respect to said first named member, a member carried by said second named member and extending longitudinally in spaced relation with respect to said first named member and adapted to be moved along the support for engagement with the releasable carrying means of the tags for releasing the articles carried thereby; a guide for said last named member, means for alternately rotating said first named member in clock-wise and anti-clockwise direction, and means carried by said second named member for controlling said last named means.
- 50 27. A device for the purposes herein set forth comprising in combination with a holder having a passage therethrough, a channel shaped support having an end portion insertable in said passage, clothes carrying tags mounted on said support and provided with members for releasing the clothes carried thereby; a standard having a passage formed therein adapted to register with the passage of said holder; a member for releasably holding said holder in operative position with the passage thereof registering with the passage of said standard; and a member working through the passage of the standard adapted to pass through the passage of the holder along the channel of said support and engage the members of the tags to release the clothes carried by the tags.
- 55 28. A device for the purposes herein set forth comprising in combination with a holder having a passage therethrough, a

channel shaped support having an end portion insertable in said passage, clothes carrying tags mounted on said support and provided with members for releasing the clothes carried thereby; a standard having a passage formed therein adapted to register with the passage of said holder; a member for releasably holding said holder in operative position with the passage thereof registering with the passage of said standard; a member working through the passage of the standard adapted to pass through the passage of said holder along the channel of said support and engage the members of the tags to release the clothes carried by the tags, and means for moving the member working through the passage of the standard through the passage of the holder and along the channel of the support and return said member to its initial position.

29. A device for the purposes herein set forth comprising in combination with a holder having a passage therethrough, a channel shaped support having an end portion insertable in said passage, clothes carrying tags mounted on said support and provided with members for releasing the clothes carried thereby; a standard having a passage formed therein adapted to register with the passage of said holder; a member for releasably holding said holder in operative position with the passage thereof registering with the passage of said standard; and a member working through the passage of the standard adapted to pass through the passage of the holder along the channel of said support and engage the members of the tags to release the clothes carried by the tags; and means for reciprocating said last named member.

30. A device for the purposes herein set forth including a holder having a central passage, a laundry tag support having an end portion insertable in said passage, a standard having a passage adapted to register with the passage of the holder, a member working through the passage of the standard and adapted to pass through the passage of the holder and along said support, and a member on said standard having a slot for the reception of the outer end portion of the holder for holding said holder in position with the passage thereof registering with the passage of said standard.

31. A device for the purposes herein set forth including a holder having a central passage, a laundry tag support having an end portion insertable in said passage, a standard having a passage adapted to register with the passage of the holder, a member working through the passage of the standard and adapted to pass through the passage of the holder and along said support, and a member on said standard having a slot for the reception of the outer end por-

tion of the holder for holding said holder in position with the passage thereof registering with the passage of said standard, said member being moved out of operative position by the outer end portion of the holder when the end portion is moved to pass into the slot of said member.

32. A device for the purposes herein set forth including a holder having a central passage, a laundry tag support having an end portion insertable in said passage, means for releasably holding said support in said passage, a standard having a passage adapted to register with the passage of the holder, a member working through the passage of the standard and adapted to pass through the passage of the holder and along said support, and a member on said standard having a slot for the reception of the outer end portion of the holder for holding said holder in position with the passage thereof registering with the passage of said standard.

33. A device for the purposes herein set forth including a holder having a central passage, a laundry tag support having an end portion insertable in said passage, means for releasably holding said support in said passage, a standard having a passage adapted to register with the passage of the holder, a member working through the passage of the standard and adapted to pass through the passage of the holder and along said support, and a member on said standard having a slot for the reception of the outer end portion of the holder for holding said holder in position with the passage thereof registering with the passage of said standard, said member being moved out of operative position by the outer end portion of the holder when the end portion is moved to pass into the slot of said member.

34. A device for the purposes herein set forth including a holder having a central passage, a channel shaped laundry tag support having an end portion insertable in said passage, a standard having a passage adapted to register with the passage of the holder, a member working through the passage of the standard and adapted to pass through the passage of the holder and along the channel of said support, and a member on said standard having a slot for the reception of the outer end portion of the holder for holding said holder in position with the passage thereof registering with the passage of said standard.

35. A device for the purposes herein set forth including a holder having a central passage, a channel shaped laundry tag support having an end portion insertable in said passage, a standard having a passage adapted to register with the passage of the holder, a member working through the passage of the standard and adapted to pass

through the passage of the holder and along the channel of said support, and a member on said standard having a slot for the reception of the outer end portion of the holder for holding said holder in position with the passage thereof registering with the passage of said standard, said member being moved out of operative position by the outer end portion of the holder when the end portion is moved to pass into the slot of said member.

36. A device for the purposes herein set forth including a holder having a central passage formed therethrough, a channel shaped support having an end portion insertable in said passage and adapted to carry laundry tags having locks to secure articles thereto, a member adapted to pass through the passage of said holder and along the channel of the support and open said locks to permit release of said articles, and means for operating said member, said means including a screw mounted for rotation and a sleeve carrying a member and working along said screw.

37. A device for the purposes herein set forth including a holder having a central passage formed therethrough, a channel shaped support having an end portion insertable in said passage, means for releasably locking said support within the passage of the holder and adapted to carry laundry tags having locks to secure articles thereto, a member adapted to pass through the passage of said holder and along the channel of the support and open said locks to permit release of said articles, and means for operating said member, said means including a screw mounted for rotation and a member having a sleeve adapted to move along said screw.

38. A device for the purposes herein set forth including a holder having a central passage formed therethrough, a channel shaped support having an end portion insertable in said passage and adapted to carry laundry tags having locks to secure articles thereto, a member adapted to pass through the passage of said holder and along the channel of the support and open said locks to permit release of said articles, and means for operating said member.

39. A device for the purposes herein set forth including a holder having a central passage formed therethrough, a channel shaped support having an end portion insertable in said passage, means for releasably locking said support within the passage of the holder and adapted to carry laundry tags having locks to secure articles thereto, a member adapted to pass through the passage of said holder and along the channel of the support and open said locks to permit release of said articles, and means for operating said member.

40. A device for the purposes herein set forth including a circular frame, holders on said frame in spaced relation with respect to each other, channel shaped supports having end portions insertable in said holders and adapted to carry laundry tags having locks for releasably carrying articles, a standard, a member passing through said standard and adapted to alternately pass through said holders and along the channel of said supports and open the locks of the laundry tags, and a member carried by said standard for alternately holding the holders in position for the passage of said second named member through said holders.

41. A device for the purposes herein set forth including a circular frame, holders on said frame in spaced relation with respect to each other, channel shaped supports having end portions insertable in said holders and adapted to carry laundry tags having locks for releasably carrying articles, a standard, a member passing through said standard and adapted to alternately pass through said holders and along the channel of said supports and open the locks of the laundry tags, a channel shaped guide for said member, a member mounted for rotation, and a sleeve carried by said rotatable member and operatively connected to said first named member for moving said member along said guide, and a member carried by said standard for alternately holding the holders in position for the passage of said second named member through said holders.

42. A device for the purposes herein set forth including a circular frame, holders on said frame in spaced relation with respect to each other, channel shaped supports having end portions insertable in said holders and adapted to carry laundry tags having locks for releasably carrying articles, a standard, a member passing through said standard and adapted to alternately pass through said holders and along the channel of said supports and open the locks of the laundry tags, and a member carried by said standard for alternately holding the holders in position for the passage of said second named member through said holders, said holding member being moved out of operative position by the outer end of the holders when said holders are moved in position for the passage of said lock opening member therethrough.

43. A device for the purposes herein set forth including a circular frame, holders on said frame in spaced relation with respect to each other, channel shaped supports having end portions insertable in said holders and adapted to carry laundry tags having locks for releasably carrying articles, a standard, a member passing through said standard and adapted to alternately pass

through said holders and along the channel of said supports and open the locks of the laundry tags, a channel shaped guide for said member, a member mounted for rotation, and a sleeve carried by said rotatable member and operatively connected to said first named member for moving said member along said guide, a member carried by said standard for alternately holding the holders 5 in position for the passage of said second named member through said holders, said holding member being moved out of operative position by the outer end of the holders when said holders are moved in position for 10 the passage of said lock opening member therethrough.

44. A device for the purposes herein set forth including a channel shaped support adapted to carry a plurality of laundry tags having locks for releasably carrying articles, and a member insertable along the channel of the support for opening the locks of said laundry tag.

45. A device for the purposes herein set forth including a holder having a central passage formed therethrough, a channel shaped support having an end portion insertable in said holder and adapted to carry a plurality of laundry tags having locks 25

for releasably carrying articles, means for releasably locking said support within the passage of said holder, and means adapted to pass through the passage of said holder, along the channel of said support and open said locks. 30

46. A device for the purposes herein set forth including a holder having a central passage formed therethrough, a channel shaped support having an end portion insertable in said holder and adapted to carry a plurality of laundry tags having locks for releasably carrying articles, means for releasably locking said support within the passage of said holder said means including a pin having a portion for engagement with 40 a depressed portion formed in the end portion of said holder, and means adapted to pass through the passage of said holder, along the channel of said support and open said locks. 45

In testimony whereof we have signed our names to this specification in the presence of two subscribing witnesses.

ANGUS F. HANNEY.
ALEXANDER GAMMELL.
